UNITED STATES PATENT OFFICE.

WILLIAM WHEELER, OF CONCORD, ASSIGNOR TO THE WHEELER REFLECTOR COMPANY, OF BOSTON, MASSACHUSETTS.

REFLECTOR.

SPECIFICATION forming part of Letters Patent No. 254,578, dated March 7, 1882.

Application filed September 9, 1881. (No model.)

To all whom it may concern:

Be it known that I, WILLIAM WHEELER, of Concord, of the county of Middlesex and State of Massachusetts, have invented a new and useful Improvement in Reflectors; and I do hereby declare the same to be described in the following specification and represented in the accompanying drawings, in which—

Figure 1 is an isometric projection, showing 10 in a double form a reflector having a reflecting-surface of such shape as would be described by the revolution about its principal axis of a curve or line of variable curvature, varying throughout its revolution by a fixed 15 law, but having always the same focus common to all the variations thereof, and an ordinate common to said curve in all its variations at some fixed point of said axis, while the ordinates drawn from any other points 20 thereof are each constantly variable throughout the whole or a part of their revolution, all as will hereinafter be shown. The elliptic curve $b' c' d'$ shows the form of a generating-curve while it is above and in the vertical 25 plane of the axis $o' o^3$. After revolving about said axis, through the quadrant $b' b^2$, during which revolution every point in said curve describes a quadrant of an ellipse, of which the ordinates to said points, before and after said 30 revolution, are respectively the conjugate semi-axes, the generating-line occupies the position $b^2 c^2 d^2$, of which the part $b^2 c^2$ is a parabolic curve. From thence the said part $b^2 c^2$, revolves about the axis $o' o^2$, through the quadrant $b^2 b^3$, when it occupies the position of the 35 line $b^3 c^3$, which is a hyperbolic curve. During said revolution every point in the said curve describes a quadrant of an ellipse, the ordinates of such points, before and after said revolution, respectively, being the conjugate semi-axes of said ellipse. The other side or half of the reflector F is formed in the same manner, the generating-curve in the position $b^4 c^4$ being a parabola. The said elliptic curve $b' c' d'$, 40 parabolic curve $b^2 c^2$, hyperbolic curve $b^3 c^3$, and parabolic curve $b^4 c^4$ have the common axis $o' o^3$, the common focus o' , and the ordinates at o^2 —namely, $o^2 c'$, $o^2 c^2$, $o^2 c^3$, and $o^2 c^4$, equal to each other. Said focus o' is the focus 45 of the reflecting-surfaces generated as above described.

Fig. 2 is a front or end elevation of the same, in which the dotted curve $x' x^2 x^3 x^4$

represents the four elliptical quadrants described by a point in the generating-curve 55 half-way between the point b' and c' ,

Fig. 3 is an isometric view of a single reflector of the same general description as that last explained, and which differs therefrom in the following regard, namely: The variable 60 curve, by the revolution of which its form is described, has in its various positions the common focus o' and a common vertex at a , or, in other words, a common ordinate at a , equal to zero.

Fig. 4. represents a front elevation of the same, in which the dotted curves $b' b^2 b^3 b^4$ consists of the two semi-ellipses described by the point b , and the curve $x' x^2 x^3 x^4$ is composed of the two semi-ellipses described by a 70 point in the generating-curve half-way between the points b' and c' .

It is to be understood that between those quadrantal parts of the forms shown in the drawings which are upon opposite sides of the vertical plane of the axes thereof there may be inserted surfaces described by the revolution of the generating-curve through any suitable angle about a vertical axis of revolution, whereby the width of the aperture of the 80 reflector may be varied.

In certain cases, when it is desired that the space immediately below the reflector shall be illuminated by direct rays from the light source, as well as by light reflected from the upper 85 part of the reflector, the lower part of the reflector may be omitted, leaving only the upper part, $b^2 b' b^4 c^2 c' c^4 d^2 d' d^4$.

Having thus described my invention, what I claim as such is as follows, viz:

1. A reflector having a reflecting-surface generated by the revolution about its principal axis of a curve, which is constantly variable throughout the said revolution, all being substantially as described.

2. A reflector having a reflecting-surface generated by the revolution about two or more axes, successively, of a curve which is constantly variable throughout its revolution about one or more of the said axes, all being substantially as set forth.

WILLIAM WHEELER.
